(57) **CLAIM**

The ornamental design for automobile wheel, as shown and described.

DESCRIPTION

1. Automobile wheel

- 1.1** : Perspective
1.2 : Front
1.3 : Back
1.4 : Top
1.5 : Left
1.6 : Enlarged

1.7 : Partially Cutaway Reference view

The article is used as an automobile wheel and the feature of the design is the overall shape of the article which is best illustrated in reproduction **1.1**. Reproduction **1.6** is an enlarged view of the part indicated by arrows A-A in reproduction **1.1**. Reproduction **1.7** is a partially cutaway reference view which form no part of the claimed design. Arrows B-B in reproduction **1.2** and arrows C-C in reproduction **1.5** indicate where a portion is cutaway from in reproduction **1.7**. Hatching in reproduction **1.7** is for illustrating the inside portions. Bottom view is omitted since it is symmetrical to the top view. Right view is omitted since it is symmetrical to the left view.
